CLAIM

The ornamental design for a guitar slide, as shown and described.

DESCRIPTION

FIG. 1 is a top perspective view of a guitar slide, showing a first embodiment of our new design;

FIG. 2 is a bottom perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a bottom plan view of FIG. 1;

FIG. 9 is a cross-sectional view, taken along line 9-9 of FIG. 3;

FIG. 10 is a cross-sectional view, taken along line 10-10 of FIG. 4;

FIG. 11 is a top perspective view of a second embodiment thereof;

FIG. 12 is a bottom perspective view of FIG. 11;

FIG. 13 is a front elevational view of FIG. 11;

FIG. 14 is a rear elevational view of FIG. 11;

FIG. 15 is a left-side elevational view of FIG. 11;

FIG. 16 is a right-side elevational view of FIG. 11;

FIG. 17 is a top plan view of FIG. 11;

FIG. 18 is a bottom plan view of FIG. 11;

FIG. 19 is a cross-sectional view, taken along line 19-19 of FIG. 13; and,

FIG. 20 is a cross-sectional view, taken along line 20-20 of FIG. 14.
